UNITED STATES PATENT OFFICE

124,540

DESIGN FOR A DISPLAY LAMP OR SIMILAR ARTICLE

Milton J. Nebenzahl, Brooklyn, and Harry M.
Gerstel, New York, N.Y.

Application October 24, 1940, Serial No. 96,050

Term of patent 7 years

To all whom it may concern:

Be it known that we, Milton J. Nebenzahl and Harry M. Gerstel, citizens of the United States of America, residing, respectively, at 1440 Ocean Parkway, Brooklyn, county of Kings, and State of New York, and at 83 Park Terrace West, New York city, county and State of New York, have invented a new, original, and ornamental Design for a Display Lamp or Similar Article, of which the following is a specification, reference being had to the accompanying drawings, forming part thereof.

In the drawings:

Fig. 1 illustrates a side elevational view of the display lamp or similar article positioned to project the light in a horizontal direction.

Fig. 2 depicts a bottom plan view of the lamp or similar article.

Fig. 3 shows a front view thereof.

Fig. 4 is a side elevational view showing the lamp in position to throw the light in an upward direction.

Fig. 5 is a side elevational view with the lamp turned in a line below horizontal.

We claim:

The ornamental design for a display lamp or similar article, as shown.

MILTON J. NEBENZAH.
HARRY M. GERSTEL.
